BOBBIN WINDER FOR SEWING MACHINES

Solomon Adler, Kew Gardens, N. Y.

Application August 30, 1946, Serial No. 693,915

12 Claims. (Cl. 112—218)

1

This invention relates to an automatic bobbin winder for sewing machines.

The bobbin winder of the conventional type of sewing machine is driven by friction contact with the hub of the balance wheel. This form of device requires frequent pressure adjustments. Also, the release of the balance wheel when winding bobbins presents a difficult problem. Such release is necessary in order to permit the bobbin winder to operate without running the stitching mechanism.

It is an object of this invention to provide a bobbin winder which dispenses with the usual frictional connection with the balance wheel and, therefore, can be used also on machines possessing no balance wheel at all. Another object is to provide a means whereby the stitching mechanism is automatically and safely disconnected upon putting the bobbin winder into operation. A still further object of the invention is a bobbin winder which is simple in construction and of small size so that it can be formed as an integral part of a completely self-contained machine of small overall dimensions, as, for instance, a portable sewing machine.

These and further advantages will appear from the following description of the invention when read in connection with the accompanying drawings, of which

Fig. 1 is an assembly plan view of the base portion of a sewing machine, embodying the automatic bobbin winder according to the invention;

Fig. 2 is a vertical section through the portion of the machine which contains the bobbin winder, showing the same in elevation;

Fig. 3 is a similar section, taken at right angles to the view of Fig. 2, and

Fig. 4 is a section on line 4—4 of Fig. 2, showing in a fragmentary view the shaft and sleeve of the thread guide with its associated follower member.

Referring to the drawings and, in particular to Fig. 1, it will be seen that the machine has a main drive shaft 1 for operation of the feed dog 2 and bobbin casing 3. A similar shaft is located in the upper portion of the machine, which is not shown in the drawings, and an appropriate vertical shafting will establish the connection between the two drive shafts, through the intermediary of bevel gear 44.

The machine is operated by a small electric motor M. A transverse shaft 4 provides the connection between the drive shafts and the motor. Secured to this shaft by a feather key is a bushing 5 on which a bevel gear 6 is disposed for

2

permanent mesh with the bevel gear 1 of the motor. By means of the feather key the shaft is lengthwise slideable in the bushing but is coupled to it for rotation. The shaft, at its forward end, carries a bevel gear 8 for engagement of a mating gear 9 which is disposed on the drive shaft. It also is provided with a bevel gear 10 which is oppositely disposed to the just mentioned front gear 8 and which serves as a connection to the gear and shaft 11 of a threading device which is not further described and is not claimed herein.

The bobbin winder proper is contained in an exterior alcove of the frame which is formed by wall portions 12 and 13 and a door-like closure 14. A carrier member 15 is secured to the rear wall 16 of the frame by screws and is lengthwise shiftable on said rear wall in slots 17 (Fig. 2). The carrier member is bent at right angles so that its portion 15a projects transversely into the machine, providing a seat for two shafts 18 and 19. Shaft 18 is adapted to carry the bobbin during the winding operation. It pierces the carrier member and has an outer slit bobbin receiving end 20 and carries at this inner end, a bushing 21 and a bevel gear 22 for engagement of the bevel 6 of the transverse shaft.

The other shaft carries a thread guide 23 and is driven by the bobbin shaft through spur gear 24 and pinion 25. This second shaft is provided with a left and right hand thread and a sleeve 26 to which the thread guide is attached.

As appears best from Fig. 4, the sleeve is pierced by a small spindle 27 which extends perpendicular to the shaft and is rotatably seated in the wall of the sleeve. Secured to the spindle at the inside is a follower member 28 which has a curved contact face for engaging the left and right hand thread of the shaft. A recess 29 in the interior wall of the sleeve provides the necessary clearance for oscillating movements of the follower.

It will be appreciated that, by means of this follower, a reciprocating movement is imparted to the sleeve when the threaded shaft is rotated. Preferably, the ends of the follower are curved inwardly towards the thread. This enables the follower to form a sliding fit in any part of the groove of the left and right hand thread without becoming wedged at intersecting points. The proper engagement with the intersecting grooves is further facilitated by the rotatable seating of the follower and an easy switch from one groove to the other upon reversal of the operation, is thus assured.

Parallel with the bobbin and thread guide shafts extends a third shaft 30 which slides in a tube 31 mounted on a bracket 32 of the frame. The latter shaft provides the holding element for the spool from which the thread is unwound in order to be rewound on the bobbin. The shaft is under action of a spring 33 contained in the tube 31. The spring tends to push the shaft outwards into the slotted line portion of Fig. 2 when the door-like closure 14 is opened. A recess 34 in an upstanding arm 35 of the closure provides a stop for the movement of the shaft when the door is closed and keeps the shaft within the confines of the frame.

The door has a connection to the angle carrier through pivot links 36, 37. The linkage is of a type wherein the direction of the motion is reversed. The carrier is, therefore, pushed inward when the door is opened and is slid outwards when the door is being closed. Another linkage 38, 39 connects the carrier with a forked collar 40 which is disposed on the extreme rear end of the slide shaft. The latter linkage is so arranged that, upon moving of the carrier to the right, the shaft is slid to the front of the machine and vice versa.

The device operates as follows:

Opening of the closure 14 exposes the three shafts of the bobbin winding mechanism for operation. The same movement effects a shifting of the angle carrier 15, 15a and of the shafts supported in it towards the interior of the machine. This brings the bevel 22 of the bobbin shaft into engagement with the slide shaft. The slide shaft 4 simultaneously is moved slightly to the rear of the machine by means of the linkage connection 38, 39 between the carrier and the clutch collar 40, which rearward movement brings about the disengagement of the bevel gear 8 and its mating gear 9 on the drive shaft of the stitching mechanism.

It will be appreciated that in this position the bobbin winding mechanism is ready to be engaged by the motor while the stitching mechanism is out of engagement. The bobbin is then placed on the bobbin shaft 18 and a spool of thread is put on the spool holding shaft 30. The thread is thereupon passed over a tension device 41 of conventional form, thence through the thread guide 23 and into the bobbin. The reciprocating motion of the sleeve 26 and thread guide will assure an even winding of the bobbin and a smooth running thread.

In order to start the motor, the machine has a rheostat starter switch. The rheostat is indicated at 42 and its scale at 43. The rheostat permits to regulate the speed of the winding and, if desired, to have the winding performed at the highest speed which can be accomplished by the machine.

Once the winding operation is completed, the door is closed after removal of the bobbin casing and thread spool. The closing of the door effects an outward sliding of the carrier member and, therefore, a disengagement of the bobbin shaft and simultaneously a forward sliding of the connecting shaft resulting in a re-engagement of the stitching mechanism.

While I have described one embodiment of my invention, it will be manifest that a number of details are open to modifications which would not constitute a departure from the spirit of the invention. I, therefore, do not wish to be limited otherwise than by the language of the appended claims.

What I claim is:

1. In a sewing machine, an automatic bobbin winder comprising in combination, a carrier member shiftably secured to the frame of the machine, a shaft mounted in said carrier member and adapted to hold the bobbin, a drive shaft for transmitting motion to said bobbin shaft, a disengageable connection between said two shafts adapted to be actuated by shifting of said carrier member, a closure for covering the bobbin holding end of the bobbin shaft, the closure being pivoted to the frame of the machine, and a linkage connection between the said closure and the said carrier member whereby the latter member is shifted upon moving of the closure so as to bring the said two shafts into relative engagement and disengagement.

2. An automatic bobbin winder, constructed in accordance with claim 1 including a lengthwise slideable arrangement of the drive shaft, a connection between the drive shaft and the stitching mechanism of the machine, the latter connection being disengageable by said lengthwise sliding of the drive shaft, a clutch collar, disposed on the drive shaft, and a linkage connecting the said clutch collar and the carrier member whereby opening of the closure and the consequent shifting of the carrier member also effects the lengthwise sliding of the drive shaft and thus the disengagement of the stitching mechanism.

3. In a sewing machine, an automatic bobbin winder comprising in combination, a carrier member shiftably secured to the frame of the machine, a shaft mounted in the carrier member and adapted to hold the bobbin, a drive shaft for transmitting a rotary motion to the bobbin shaft, a disengageable connection between said two shafts, means to actuate said connection by shifting the carrier member, a second shaft mounted in the carrier member and having a left and right hand external thread, a sleeve carried by the said second shaft, a follower member secured to said sleeve and adapted to engage the left and right hand thread for transmitting a reciprocating motion to the sleeve, a thread guide carried by the sleeve, means for transmitting the rotary motion of the bobbin shaft to said second shaft, and a holder for a spool of cotton, the thread passing from the spool through the thread guide to the bobbin disposed on the bobbin shaft.

4. In a sewing machine, an automatic bobbin winder comprising, in combination, a carrier member shiftably secured to the frame, a shaft mounted in the carrier member and adapted to hold the bobbin, a drive shaft for transmitting a rotary motion to the bobbin shaft, a disengageable connection between said two shafts, means to actuate said connection by shifting the carrier member, a second shaft journaled in the carrier member, said latter shaft having an endless left and right hand external thread, a sleeve, carried by said second shaft, a follower projecting internally from said sleeve, the follower being rotatable about an axis perpendicular to the axis of the sleeve carrying shaft and being of a form adapted to engage the groove of the intersecting threads, a thread guide carried by the sleeve, means for transmitting the rotary motion of the bobbin shaft to said second shaft, and a holder for a spool of cotton, the thread passing from the spool through the thread guide to the bobbin disposed on the bobbin shaft.

5. In a sewing machine, a bobbin winder constructed in accordance with claim 4 wherein the follower member is provided with an arcuate

contact face, with ends curving towards the said threaded shaft, for sliding engagement with the grooves of the thread.

6. In a sewing machine, an automatic bobbin winder comprising, in combination, a carrier member shiftably secured to the frame of the machine, a shaft journaled in the carrier member and adapted to hold the bobbin, a slideable drive shaft for transmitting motion to said bobbin shaft, a disengageable connection between said two shafts, the carrier member being adapted, upon shifting, alternatively to engage and disengage the said connection, means to effect the shifting of the carrier member, a shafting for transmitting motion to the stitching mechanism of the machine, a means disposed on the drive shaft for connection to the said shafting, a linkage between said carrier shifting means and said slideable drive shaft adapted to effect a simultaneous shifting of the carrier member and shifting of the drive shaft, so that, when the bobbin shaft is brought into engagement with the drive shaft, the latter shaft is disengaged from the shafting of the stitching mechanism.

7. In a sewing machine, an automatic bobbin winder comprising, in combination, a carrier shiftably secured to the frame of the machine, a shaft journaled in the carrier and adapted to hold the bobbin, a drive shaft for transmitting motion to the bobbin shaft, the two shafts being adapted selectively to be brought into engagement and disengagement by shifting of the said carrier, a tubular member secured to the frame, a spindle adapted to hold a spool of cotton, the spindle being slideable in the said tubular member, means forcing the spindle outwardly, a closure for covering the outer end of the bobbin shaft, said closure being pivoted to the frame, an abutment for the outside end of said spindle, disposed on said closure and adapted to force the spindle into the tubular member upon inward movement of the closure, and a linkage connecting said closure to the carrier adapted to bring the bobbin shaft into engagement with the drive shaft upon outward movement of the closure.

8. In a sewing machine, an automatic bobbin winder comprising in combination a shaft for holding the bobbin, means for engaging and disengaging said shaft with a source of motive power, a movable closure member for covering the bobbin holding end of said shaft, and an operative connection between said closure member and said power engaging and disengaging means, whereby the latter means are actuated upon moving of said closure member.

9. In a sewing machine, an automatic bobbin winder comprising in combination a shaft for

holding the bobbin, a drive shaft for transmitting motion to said bobbin shaft, a disengageable connection between the said two shafts, a movable closure member for covering the bobbin holding end of said bobbin shaft, and means operatively linking said closure member to said disengageable connection whereby the latter is actuated upon moving of said closure member.

10. In a sewing machine, an automatic bobbin winder comprising in combination a shaft for holding the bobbin, a drive shaft for transmitting motion to said bobbin shaft, a disengageable connection between the said two shafts, a pivoted closure member for covering the bobbin holding end of said bobbin shaft, and a linkage connection between said pivoted closure member and said disengageable connection whereby the latter is actuated upon moving of said closure member.

11. In a sewing machine, an automatic bobbin winder constructed in accordance with claim 9 and including an auxiliary shaft having a left and righthand external thread, a sleeve carried by the said auxiliary shaft, a follower member secured to said sleeve and engageable by the left and righthand thread for transmitting a reciprocating motion to the sleeve, a thread guide formed on said sleeve, and means for transmitting motion to the said auxiliary shaft, whereby the thread guide is adapted to pass the thread to the bobbin and to permit the winding of a bobbin of substantially uniform thickness.

12. In a sewing machine, an automatic bobbin winder constructed in accordance with claim 9 and including an auxiliary shaft having a left and righthand external thread, a sleeve carried by the said auxiliary shaft, a follower member projecting internally from said sleeve, the follower member being rotatable about an axis perpendicular to the axis of the sleeve carrying shaft and being of a form adapted to engage the groove of the intersecting threads, a thread guide carried by the sleeve, and means for transmitting the motion of the bobbin shaft to the auxiliary shaft, whereby the thread guide is adapted to pass the thread to the bobbin for obtaining windings of substantially uniform thickness.
